By Richard B. Dunn ^{Attorney}

UNITED STATES PATENT OFFICE.

JULIUS L. EMERY, OF ALTOONA, PENNSYLVANIA.

DESIGN FOR A NUTCRACKER.

Application filed October 19, 1921. Serial No. 508,884. Term of patent 3½ years.

To all whom it may concern:

Be it known that I, JULIUS L. EMERY, a citizen of the United States, residing at Altoona, in the county of Blair and State of Pennsylvania, have invented a new, original, and ornamental Design for a Nutcracker, of which the following is a specification, reference being had to the accompanying drawing, forming part thereof.

The figure is an elevation of a nutcracker, showing my new design.

I claim:—

The ornamental design for a nutcracker as shown.

JULIUS L. EMERY.
